UNITED STATES PATENT OFFICE

JACOB VAN ECK AND FEKKO FEKKES, OF ROTTERDAM, NETHERLANDS; SAID FEKKES
ASSIGNOR TO HENDRIK FEKKES

ELECTRIC INCANDESCENT LAMP

Application filed January 4, 1930, Serial No. 418,616, and in Belgium August 9, 1929.

It has been tried often and in many ways to render the light emitted by incandescent electric lamps as efficient as possible, by means of reflectors.

5 A very simple and cheap way of obtaining same will be described hereafter with reference to the figures of the accompanying drawing.

Fig. 1 is a sectional view of a lamp;

10 Fig. 2 is another sectional view, but only of a portion of a lamp;

Fig. 3 is a sectional view of the upper portion of a lamp according to a different embodiment;

15 Fig. 4 is a section on line IV—IV of Fig. 1;

Fig. 5 is a section on larger scale of the neck of the lamp shown in Fig. 1.

With reference to these figures, a glass bulb *a* is formed with a neck *b* and *c* is a separate glass element.

According to Fig. 1, the cross section of the bulb *a* is firstly parabolic from *j* to *k* and then straight from *k* to *l*, and the cross section of the glass element *c* is parabolic from *m* to *n*. The glass element *c* may or may not be provided at its upper end with a flange, to which the neck *b* is sealed, whereas the lower end of said element *c* has a tubular shape. The electrodes or leading-in wires pass 30 through this tubular portion and are sealed therein. Under said glass element *c* is sealed a small pedestal *f*, in which the supporting wires for the filament are fastened. These supporting wires may be straight, 35 curved or bent at right angles.

The filament is located in a plane variably spaced from the vertex of the annular parabolic portion.

The electrodes or leading-in wires are 40 curved or bent inside the bulb, in order to increase their length and thereby not to heat the glass to an undesirable degree.

An opening and short pipe are shown at *g*, which serve the purpose of extracting the air 45 and filling the bulb with the desired gases, after which operation said pipe *g* is sealed at a very short distance from the neck *b*. For this purpose, an inner pipe may also be employed, said pipe forming an opening through *c* which the passage of the wires through *c*

takes place, or therebelow, which pipe is sealed after use at its top end.

Fig. 3 shows a section of the upper portion of a lamp, in which parts of the bulb are straight, but it must be understood that this upper portion of the bulb may also comprise straight and curved portions. Reflecting means are provided on the element *c*, starting from a little above the level *m* and ending at the level *n*, and on a portion of the neck *b* and on the bulb *a* from *j* to *k* or *l* or further. These reflecting means may also be provided on the element *c* and the bulb *a* to terminate in a plane inclined to the lamp axis, such as *x*—*y*.

The reflecting means are provided inside the glass or on the outer face of the neck, bulb and element *c*, i. e. outside the inner part of the lamp. The reflecting means is coated with a substance, which does not conduct electricity, when it is provided on the outer faces of the elements. Care must, of course, be taken that the two electrodes do not come in contact with each other or with the reflecting means.

We claim:

1. An incandescent electric lamp, comprising a glass bulb, a glass neck forming an extension of said bulb, an inner glass element sealed to the bulb at the top end thereof and terminating in a tubular part, leading-in wires passing through said tubular part and sealed therein, a small pedestal sealed to said tubular part, supporting wires for the filaments fastened to said pedestal and an opening and short pipe at the top end of the neck for gas extracting and filling purposes, the pipe being cut short near the neck.

2. An incandescent electric lamp having a reflecting portion arranged around the filament, the surface of this portion being substantially that generated by the revolution of a parabola about a line parallel to its axis, the bulb of the lamp having a neck of considerable section and a glass element of corresponding section and similar conformation sealed in said bulb, the glass element extending inside the bulb in the shape of a tapered tubular projection, said projection forming with the adjacent bulb por-

tion the above-mentioned parabolic reflecting portion, a glass pedestal secured to said projection, radial supporting wires for the filament supported by said pedestal, and electric leads passing through said element.

- 6 3. An incandescent electric lamp having a reflecting portion arranged around the filament, the surface of this portion being substantially that generated by the revolution
10 of a number of straight segments forming an angle with each other and approximating to a parabola about a line parallel to the axis of the parabola, the bulb of the lamp having a neck of considerable section and a
15 glass element of corresponding section and similar conformation sealed in said bulb, the glass element extending inside the bulb in the shape of a tapered tubular projection, said projection forming with the adjacent
20 bulb portion the above-mentioned reflecting portion, a glass pedestal secured to said projection, radial supporting wires for the filament supported by said pedestal, and electric leads passing through said element.

25 In testimony whereof we signed hereunto
our names.

J. VAN ECK.
F. FEKKES.
